SIGN MAKING OUTFIT AND WELDER

Harry Alexander, New York, N. Y.

Application July 18, 1938, Serial No. 219,739

6 Claims. (Cl. 219—21)

This invention relates to new and useful improvements in a sign making outfit and letter welder.

The invention has for an object the provision of a sign making outfit which is characterized by letters or designs coated on the back side with thermo-plastic adhesive, and a heated welder by which the letters or designs may be applied in a specific manner to a sign body. It is proposed 5 that the letters or designs be constructed so that they may be freely moved about and placed in positions in proper alignment with each other to produce the sign.

It is further contemplated that each of the 15 letters or designs be temporarily held in position by touching the same at one or more spots with the heated welder. After the sign has been completed, if it is required to shift any of the letters or designs, this may be accomplished quite easily. When one is satisfied with the arrangement 20 it is proposed that the heated welder be used to iron down the letters and designs throughout their entire compass so that they are permanently attached on the sign body.

25 The invention has for an object the construction of a welder which is particularly adapted to be conveniently held in one's hand and be used as an iron for softening adhesive material upon letters to be used on a sign, and for ironing these 30 letters on the sign.

The invention contemplates to construct the welder in a manner so that it is normally connected with an electric cord when it is desired to heat up the welder. The arrangement is to be 35 such that the heated welder may be removed from the cord connection and it is then ready for use as previously explained.

More specifically, the invention contemplates characterizing the welder by a body portion built 40 up from several electrical sockets and plugs in a manner to form an inexpensive unit which may be conveniently gripped and handled.

The invention further proposes providing an electric cord for supplying current to the electric 45 connections, and connected at one end of said built-up body.

The invention also contemplates the use of an electric cigar lighter type of heater to be mounted in one of the sockets and located at the other 50 end of the body and to comprise the unit for supplying the heat for the welder.

As another object of this invention it is proposed to make use of an iron disc engaged over the cigar lighter type heater for absorbing and 55 holding heat from the lighter.

It is proposed to provide a novel cap arrangement for holding the disc in various spaced positions with respect to the lighter.

For further comprehension of the invention, and of the objects and advantages thereof, reference will be had to the following description and accompanying drawing, and to the appended claims in which the various novel features of the invention are more particularly set forth.

5 In the accompanying drawing forming a material part of this disclosure:

Fig. 1 is a perspective view of a welder constructed according to this invention and shown as it would appear when one is using the welder to secure sign letters in position.

15 Fig. 2 is a side elevational view of the heater per se.

Fig. 3 is a fragmentary elevational view with a portion thereof broken away to illustrate interior parts.

20 Fig. 4 is a perspective view of the cigar lighter per se used in this device.

Fig. 5 is a perspective view of the iron disc.

Fig. 6 is an elevational view similar to Fig. 3, with portions thereof broken away to illustrate 25 interior parts, but showing the interior parts in a different position.

Fig. 7 is a fragmentary elevational view of a portion of a heated welder constructed according to another embodiment of this invention, a portion thereof being broken away to illustrate interior parts.

30 The welder for applying sign letters, according to this invention, includes a body built up from several electric sockets and plugs connected together. Specifically, there is a socket 10 into which a screw plug 11 is threadedly engaged.

This screw plug is of the type having openings 12 for receiving the prongs of another electrical connection, such as the long body socket 13. 40 This socket 13 has prongs 14 engaged through the openings 12. In the other end of the electric socket 13 a conventional electric cigar lighter is threadedly engaged.

45 This cigar lighter comprises a porcelain body 15 upon one end of which there is a metallic screw thread contact shell 16 and an end contact 17. On the other end of the porcelain body 15 there is a fine incandescent wire winding 18 comprising the heating element, connected with the end contact and contact shell in a conventional manner, not shown on the drawing. A

50 mica disc 19 is engaged over the incandescent wire 18 and is held in position by a cap 20 having straight sides 20a.

An iron disc 22 is engaged over the mica of the cigar lighter. A cap 23 encases the iron disc 22 and the end portion of the electric cigar lighter. A means is provided for holding said cap in adjusted extending positions for varying the space between the disc 22 and the lighter. This means includes a heat resistant body 24, such as a Bakelite body, in the form of a tubular member securely connected with the rear edge of the cap 23. This body 24 is formed with threads 24^a threadedly engaged upon the end of the body of the electric socket 13. An electric cord 25 is connected with the socket 10.

The welder is adapted to be held in one's hand 15 in a manner similar to the normal holding of a pencil, for example as shown in Fig. 1. The cord 25 extends away from the top end of the heater and is intended to be connected with an electric circuit not shown on the drawing. Sign letters 27 are formed with adhesive material 28 on one of their sides. The adhesive material is of a type which becomes sticky with the application of heat. The letters 27 may be attached upon a window pane or a sign board, or on any 20 other flat surface in the following manner:

The letters and designs are placed upon a sign body and shifted and moved until they are in proper relative positions. They are then temporarily attached by touching a heated welder 30 to one or more points of each of the letters. The completed sign may then be inspected for accuracy. If required, the letters and designs may be shifted. If satisfactory, the letters and designs are permanently attached by ironing the 35 same down with the use of the heated welder. The flat surface of the cap 23 is engaged against the top faces of the letters or designs during this ironing operation.

When desired, the body 24 may be turned to 40 increase the space between the inside face of the flat wall of the cap 23 and cigar lighter. When this is done the iron disc 22 will move out of contact with the cigar lighter. The distance between these parts may be controlled by turning the body 24. In this manner the passage of 45 heat may be regulated. Should the heater become too hot, the parts are adjusted as shown in Fig. 6 with the disc 22 moved out of contact.

The disc 22 is for the purpose of absorbing and 50 holding the heat. The cap 23 is also formed with a plurality of openings 23^a which are normally covered by the straight side walls 23^b of the cigar lighter. When the body 24 is screwed outwards to the position shown in Fig. 6, the openings 23^a 55 communicate with the space between the end of the cigar lighter and the disc 22. Thus a passage to the atmosphere is created which assists in rapidly cooling the heater. This is particularly advantageous should the heater become too hot and show signs of burning the letters.

In Fig. 7 another embodiment of the invention has been disclosed. In this form there is a long body socket 13' on the lower end of which a metallic cap 23' is removably engaged. A cigarette lighter 15 is threadedly engaged into the socket 13' and is encased by the cap 23'. This cigarette lighter has a shell contact 16 and an end contact 17, as previously described. Interposed between the outer extremity of the lighter 15 and the cap 23' there is one or more metallic discs 22'. These discs are tightly packed in the space by forcing the cap 23' upwards as far as it will go. The disc or discs 22' are used to retain and conduct heat from the lighter 15 through the 70 end wall of the cap 23'. The cap 23' friction-

ally maintains its position on the socket 13'. In other respects this form of the invention is similar to the previous form and similar parts may be identified by corresponding reference numerals.

While I have illustrated and described the preferred embodiments of my invention, it is to be understood that I do not limit myself to the precise constructions herein disclosed and the right is reserved to all changes and modifications 10 coming within the scope of the invention as defined in the appended claims.

Having thus described my invention, what I claim as new, and desire to secure by United States Letters Patent is:

1. A welder for applying sign letters, comprising a body built up from several electric sockets and plugs connected with each other, an electric cord for supplying current to said electric connections and connected at one end of said body, an electric cigar lighter mounted in one of said sockets and located at the other end of said body, an iron disc engaged over the said cigar lighter for absorbing and holding heat from the lighter, a cap encasing said disc and lighter. 20

2. A welder for applying sign letters, comprising a body built up from several electric sockets and plugs connected with each other, an electric cord for supplying current to said electric connections and connected at one end of said body, 30 an electric cigar lighter mounted in one of said sockets and located at the other end of said body, an iron disc engaged over the said cigar lighter for absorbing and holding heat from the lighter, a cap encasing said disc and lighter, and means 35 for holding said cap in adjusted extended positions for varying the space between said disc and lighter.

3. A welder for applying sign letters, comprising a body built up from several electric sockets and plugs connected with each other, an electric cord for supplying current to said electric connections and connected at one end of said body, an electric cigar lighter mounted in one of said sockets and located at the other end of said body, 45 an iron disc engaged over the said cigar lighter for absorbing and holding heat from the lighter, a cap encasing said disc and lighter, and means for holding said cap in adjusted extended positions for varying the space between said disc and 50 lighter, said body comprising an end socket to which said cord is connected, a screw socket with openings engaged therein, a long body socket with prongs engaging in said openings, and a tubular body connected with said cap and extending over the end portion of said long socket body. 55

4. A welder for applying sign letters, comprising a body built up from several electric sockets and plugs connected with each other, an electric cord for supplying current to said electric connections and connected at one end of said body, an electric cigar lighter mounted in one of said sockets and located at the other end of said body, an iron disc engaged over the said cigar lighter for absorbing and holding heat from the lighter, a cap encasing said disc and lighter, means for holding said cap in adjusted extended positions for varying the space between said disc and lighter, comprising a tubular body rigidly 60 connected with the inner end of the cap, and said tubular body being threadedly engaged on said body. 65

5. A welder for applying sign letters, comprising a body built up from several electric sockets 70

- and plugs connected with each other, an electric cord for supplying current to said electric connections and connected at one end of said body, an electric cigar lighter mounted in one of said sockets and located at the other end of said body, an iron disc engaged over the said cigar lighter for absorbing and holding heat from the lighter, a cap encasing said disc and lighter, means for holding said cap in adjusted extended 5 positions for varying the space between said disc and lighter, comprising a tubular body rigidly connected with the inner end of the cap, and said tubular body being threadedly engaged on said body, said electric cigar lighter including a circular end portion with a mica disc extended over an incandescent wire, and a cap engaged over the edge portions of the mica disc and having a straight wall. 10
- 15 6. A welder for applying sign letters, comprising a body built up from several electric sockets and plugs connected with each other, an electric cord for supplying current to said electric
- 15 20 connections and connected at one end of said body, an electric cigar lighter mounted in one of said sockets and located at the other end of said body, an iron disc engaged over the said cigar lighter for absorbing and holding heat from the lighter, a cap encasing said disc and lighter, means for holding said cap in adjusted extended 5 positions for varying the space between said disc and lighter, comprising a tubular body rigidly connected with the inner end of the cap, and said tubular body being threadedly engaged on said body, said electric cigar lighter including a circular end portion with a mica disc extended over an incandescent wire, and a cap engaged over the edge portions of the mica disc and having a straight wall, and said cap being formed with side apertures normally closed by said straight wall and adapted to communicate with the compass within the cap when the cap is adjusted into an extended position. 10
